UNITED STATES PATENT OFFICE

105,067

DESIGN FOR A RADIO ANTENNA FOR VEHICLES

Lee Roy L. Williams, Minneapolis, Minn.

Application April 26, 1937, Serial No. 68,973

Term of patent 7 years

To all whom it may concern:

Be it known that I, Lee Roy L. Williams, a citizen of the United States and residing in the city of Minneapolis, county of Hennepin, and State of Minnesota, have invented a new, original, and ornamental Design for a Radio Antenna for Vehicles, of which the following is a specification, reference being had to the accompanying drawing, forming a part thereof, wherein:—

Fig. 1 is a perspective view of a radio antenna for vehicles showing my new design;

Fig. 2 is a top plan view thereof; and

Fig. 3 is a side elevation of the same.

I claim:

The ornamental design for a radio antenna for vehicles, substantially as shown.

LEE ROY L. WILLIAMS.
